UNITED STATES PATENT OFFICE.

CHARLES JOSEPH WESTON, OF PHILADELPHIA, PENNSYLVANIA.

MOTOR MECHANISM FOR MILLS.

SPECIFICATION forming part of Letters Patent No. 654,083, dated July 17, 1900.

Application filed November 1, 1899. Serial No. 735,502. (No model.)

To all whom it may concern:

Be it known that I, CHARLES JOSEPH WESTON, a citizen of the United States, residing at Philadelphia, in the county of Philadelphia and State of Pennsylvania, have invented certain new and useful Improvements in Motor Mechanism for Mills; and I do declare the following to be a full, clear, and exact description of the invention, such as will enable others skilled in the art to which it appertains to make and use the same.

The invention has relation to motor mechanism for grinding, chopping, and churning mills, and more particularly to means for accelerating the speed of such machines, thereby reducing the time and labor required to grind, chop, or churn the material.

The object of the invention is to provide a device of this character which shall be simple of construction, durable in use, and comparatively inexpensive of production and which may be easily applied to machines of this description.

With this object in view the invention consists in certain features of construction and combination of parts, which will be herein-after fully described and claimed.

In the accompanying drawings, Figure 1 is perspective view of a coffee-mill, illustrating the application of my invention. Fig. 2 is a perspective view of my device applied to the wheel of the mill; and Fig. 3 is a view, on an enlarged scale, taken centrally through the hub of the mill.

In the drawings, 1 denotes the mill, which may be of any well-known or approved construction, provided with the fly-wheels 2.

3 denotes a clamp, preferably consisting of the ring 4 and a disk 5, which are secured together by bolts 6, that extend between the spokes of the wheel. The face of this disk 5 is provided with a hub 7, formed with a reduced annular shoulder 8, integral with which are a pinion 9 and a stud-bearing 10.

11 denotes the frame, preferably U-shaped and provided at its upper end with an enlarged bearing-aperture to engage the annular shoulder 8 and with a small bearing-aperture to engage the stud-bearing 10. A set-screw and a washer are secured to the end of the stud-bearing and serve to prevent the lateral displacement of the frame.

13 denotes a gear-wheel, the axis 14 of which is journaled in the frame and is provided with

a head 15, formed with an aperture 16 to receive a crank 18, which is adjustably secured therein by a set-screw 19.

20 denotes a chain which connects the frame to the floor and serves to prevent the rotation of the frame as the mill-wheels are 60 revolving. Any other means may be employed in lieu of a chain for preventing the rotation of the frame. It is evident that by gearing the pinion with the large gear upon the rotation of the crank an accelerated speed 65 will be imparted to the machine, thus saving much time and labor in the act of grinding coffee.

If it be desired to adjust the sweep of the crank, this may be easily accomplished by 70 loosening the set-screw and moving the crank either in or out, as the case may be.

From the foregoing description, taken in connection with the accompanying drawings, the construction, operation, and advantages 75 of the device will be readily apparent without requiring an extended explanation.

It is evident that the device may be attached to any of the mills now in use and for this reason may be placed upon the market 80 as an article of manufacture and sold separately and applied to the mills by purchasers themselves. It will also be understood that various changes in the form, proportion, and the minor details of construction may be resorted to without departing from the spirit 85 or sacrificing any of the advantages of this invention.

Having thus described the invention, what is claimed, and desired to be secured by Letters Patent, is—

The combination with the fly-wheel of a coffee-mill, of a clamp secured thereto and consisting of a ring and a disk bolted together, the disk being formed with an annular shoulder and with a pinion and a stud-bearing, a frame having bearing-apertures to engage the annular shoulder and the stud-bearing, a gear-wheel journaled in said frame, and a crank for rotating the gear-wheel, substantially as and for the purpose set forth.

In testimony whereof I have hereunto set my hand in presence of two subscribing witnesses.

CHARLES JOSEPH WESTON.
